UNITED STATES PATENT OFFICE.

EUGENE GASSMANN, OF BROOKLYN, NEW YORK, ASSIGNOR TO EISEMANN MAGNETO CO., OF NEW YORK, N. Y., A CORPORATION OF NEW YORK.

ELECTRICAL IGNITION SYSTEM.

1,178,067.

Specification of Letters Patent.

Patented Apr. 4, 1916.

Application filed October 30, 1913. Serial No. 798,266.

To all whom it may concern:

- Be it known that I, EUGENE GASSMANN, a citizen of Germany, and a resident of the borough of Brooklyn, county of Kings, and 5 State of New York, have invented a certain new and useful Improvement in Electrical Ignition Systems for Internal-Combustion Engines, of which the following is a full, clear, and exact specification.
- 10 This invention relates to ignition systems for internal combustion engines, its object is to provide means for producing a strong, voluminous ignition spark, to insure ignition also at such times when the magneto 15 is run at a low speed—for instance—when the engine is being started by cranking, or a self-starter, or when otherwise only a weak primary current is available; and the invention consists in the hereinafter specified improvement in the construction of such 20 igniting devices, whereby an intensifying of the current is effected, producing, in the induction coil, a high tension current of sufficient volume to produce under such conditions an intense, voluminous spark in the 25 cylinder of the engine.

The construction and arrangement of this improvement, which is applicable to electric ignition devices having a fixed, or a rotating armature, and to single or double ignition systems, is illustrated in the accompanying drawings, wherein—

Figure 1 is a diagram showing the arrangement and connections of the parts of 35 a double ignition system, wherein the winding of the armature is stationary; Fig. 2 is a diagram showing the arrangement and connections of the parts of a double ignition system, according to my invention, wherein 40 the armature is rotated; Figs. 3 and 4 are diagrams of ignition systems arranged similarly, as shown in Figs. 1 and 2 respectively, but showing also the arrangement and connections of a commutator in such ignition 45 systems devised according to my invention. Fig. 5 is an end view, or front elevation, of the commutator disk.

Referring to Fig. 1, showing the arrangement of the parts and their connections for 50 double ignition systems, wherein the winding of the armature is stationary, A represents the core, P the primary and S the secondary coil of the armature winding of the magneto; B the battery; I a mechanically 55 operated circuit breaker, m being its station-

ary and n its movable arm; C represents a condenser; c and c' being its connections in the circuit, parallel to the circuit breaker I; v and v' are wires of the magneto circuit to and with the circuit breaker I, the wire v' 61 connecting at p' with the armature winding of the magneto; b, b' and b² are wires of the battery circuit, connecting at p with the primary coil of the armature winding; D designates a switch for connecting, and for 65 cutting out, the battery; t and t' are the sparker terminals, the latter being also the terminal of the secondary armature winding S of the magneto; G is the mass, and g the grounding connecting therewith. In this 70 arrangement, it will be noted, the armature winding of the alternating current generator A is connected with the constant current source, the battery B, and consequently, when the arm of switch D is shifted to connect the points d' and d² in the battery circuit, and the contacts of the interrupter I closed, the current from the battery B will 75 flow through wire b', switch D and wire b² into the primary coil P, wherewith wire b² 80 connects at p, and through it to wire v', connected to the other terminal of the primary coil at p', from there through the contact arms n and m and wire v to the magneto and through wire b back to the battery. 85 This battery current reinforces and augments whatever current there may be produced by the magneto, while it is operated at a low speed, as for instance, on the starting of the engine, or whenever the engine is 90 run at a low speed. The confluence of the electric currents from both sources, whenever the battery current is turned on, results in producing, when the primary circuit is interrupted, a strong, or rather impulsive, 95 flow of induced current, of high intensity and volume, in the secondary coil, P of the magneto, and the discharge of an intense and voluminous spark at the terminal t', and thus insures the safe ignition of the 100 charge, irrespective of the speed at which the alternating current generator may then be run.

The battery current may be cut off by shifting switch D to the position connecting 105 points d and d² as shown in the drawings, whereupon the magneto alone operates to produce the ignition, its low tension current flowing then in the same circuit as explained, but reverts from wire b through wire b³, 110

switch D, and wire b^2 , into the primary coil P; the high tension current flows through the secondary, induction coil S, to the spark terminal t' whenever the circuit of the primary current is interrupted.

Besides effecting the above stated object of my invention, this improvement simplifies and cheapens the construction of such double ignition system, by dispensing with the induction coil in the battery circuit and its attendant apparatus and connections, and yet permits the employment of the battery ignition, in case of a break down of the magneto, with equal facility and effect, the secondary magneto winding serving then as the induction coil for the battery ignition.

The diagram Fig. 3, illustrates the arrangement and connections of the parts of an ignition device, in which the armature winding is stationary, the same as shown in Fig. 1, but combined with a commutator. Its corresponding parts and wiring connections are designated by the same reference letters and numerals as in Fig. 1. The commutator is composed of two disks, designated respectively H and H', which are stationary, the carbon brushes f, holder N, formed in the shape of cog-wheel, rotatably mounted on stud L, and which may be driven by a transmission from the engine shaft, and their connecting conduits. Disks H and H' are alike, though reversely, equipped. On each there is an annular field, divided into four segments, (see Fig. 5) the one designated J (and J' respectively) being the contact segment, the one designated G is the ground, or mass, and the two designated O, intervening between J and G are insulations. Segments J and J' are made of conductive metal and they, and their connecting wires b^2 , are insulated by bushings h'. The carbon brushes f are set in insulating bushings h in the rotating brush holder N in positions to traverse the annular fields of the commutator disks, and are yieldingly pressed against the disks by metallic springs f'. Segment J of disk H is connected by wire b^2 , with the primary winding P of the stationary armature of the alternating current generator, and the corresponding segment J' of the disk H' is connected by the wire b^2 , through switch D and wire b' , to one pole of the battery B; the other pole of the battery is grounded by wire b, terminating in the mass of disk H'. Thus when switch D is in the position, indicated in full line in Fig. 3, the battery current will flow through wire b' , switch D, wire b^2 , segment J', carbon brushes f, segment J and wire b^2 into the primary winding P of the armature. By shifting the switch D to point d^3 , the position indicated in dotted lines, the battery is cut out, and by shifting the switch D' from point x' to point v' , wires x and v , the electrical connection from segment J to the

anchor of the magneto A, are connected, and the magneto circuit closed. The operations of the ignition device constructed as shown in Fig. 3, take place in the same way as explained with reference to Fig. 1, the arrangement and connections of the other elements being the same.

In the arrangement, illustrated in diagrams Fig. 2 and 4, which are devised for an ignition apparatus, having a rotating armature, a third coil T is provided, whose terminals are connected one to the primary coil P, and the other to the secondary coil S of the armature. The wiring connections are made as follows: The wire b^2 of the battery circuit is connected at s' to the joined terminals of the secondary armature winding S and of the coil T, and the wire v' to the joined terminals at p' of the coil T, and of the primary armature winding P, whose other terminal is connected to the rotating core of the magneto. All other parts and wires are connected in the same way as those of the system illustrated in Fig. 1, except that no connection is made between the switch point d , and the wire b of the battery circuit.

When the switch D is shifted, to close the battery circuit, as, for instance, at the starting of the engine, and the contact points of the interrupter I are closed, the battery current flows through wire b' , switch D, wire b^2 , the coil T, wire v' the levers n and m and wire v to the magneto, and through wire b to the battery as there is practically no resistance to the flow of the current at I and there is resistance to its passage through the winding P. This current is augmented by whatever current is produced by the magneto, and is flowing through the primary winding P of its armature. When the primary circuit is interrupted, by the separating of the contacts m and n , the flow of the battery current through wire v' is stopped, and its flow through the winding P being resisted, the high tension of the current induced in the secondary winding S of the armature and flowing to the terminal t' , where the spark is discharged, is thereby increased. It results in no detriment in the functioning of the ignition device that the circuit through battery is closed continuously, as long as the switch D is closed, because the battery current always acts in support of—or supplements—the action of the magneto current, the system being devised to operate either with the battery and magneto current combined, or with the magneto alone. When the battery B is cut out, by shifting the switch D to the point d , the magneto operates the ignition in the same way as in any other single or double ignition system, the coil T functioning then as a part of the secondary armature winding S, whereby the high tension current, induced therein, when

the primary circuit is interrupted, is correspondingly intensified.

The adding, in the arrangements shown diagrammatically in Figs. 2 and 4, of the third coil T on the armature of the magneto, and the connecting of it to the primary, and also to the secondary winding of the armature, and to the battery and magneto circuits, as described, also prevents all loss of current in the transmission from the contact ring to the brush, which otherwise must be provided in every apparatus in the magneto and in the battery circuit as well.

In the arrangement illustrated in Fig. 4, the one commutator disk H, is secured to and rotates with, the armature of the magneto and the wiring connections are correspondingly simplified in the arrangement shown in Fig. 4. In this arrangement the segment J of the commutator disk H is connected by the wire b² to the joined terminals of the coil T, and of the secondary armature winding S, at s' and the brushes f and f' are connected, one by the wire b, and the other by wire b², through switch D and wire b', with the poles of the battery B. The connecting, and the cutting out, of the battery is effected by shifting the switch D, as explained with reference to the diagram Fig. 2. When switch D is set to close the battery circuit and the contact points of the circuit breaker I are closed, the battery current flows during the periods when brush f contacts with the segment J of the disk H, through the coil T and wire v', etc., and the same effect is produced by the co-operation of the co-acting elements of the system, as explained with reference to the diagram in Fig. 2. When the battery B is cut out, the device operates as a single and in case of a break in the operation of a magneto, the device may be operated as a single (battery) ignition acting in both cases the same way explained above.

I claim as my invention:

1. An electrical ignition system for internal combustion engines comprising an alternating current generator, a primary circuit, an interrupter in the primary circuit, a high tension circuit and a sparking device connected therein; a coil on the armature of the generator connected with the terminals of the primary and of the secondary armature windings of the generator; a battery; an electrical conduit from the battery connecting with the joined terminals of the coil and of the secondary armature winding of the generator; a switch in the conduit; and an electrical conduit completing the battery circuit; substantially as herein shown and described.

2. An electrical ignition system for internal combustion engines comprising an alternating current generator, a primary circuit, an interrupter in the primary circuit, a high

tension circuit and a sparking device connected therein; and an intermediate coil between the primary and the secondary windings of the alternating current generator, and connecting therewith; a commutator electrically connected with the primary armature winding of the generator; a battery; electrical conduits from the poles of the battery to the commutator; a switch therein and an electrical conduit from the cut out terminal of the switch to the alternating current generator, substantially as herein shown and described.

3. An electrical ignition system for internal combustion engines comprising an alternating current generator, a primary circuit, an interrupter in the primary circuit, a high tension circuit and a sparking device connected therein; a coil on the armature of the generator connected with the terminals of the primary and of the secondary armature windings of the generator; a commutator electrically connected with the joined terminals of the coil and of the secondary armature winding of the generator; a battery; electrical conduits from the poles of the battery to the commutator; and a switch in the conduit from the battery to the commutator, substantially as herein shown and described.

4. The combination in an electrical ignition system for internal combustion engines comprising an alternating current generator, a primary circuit, an interrupter in the primary circuit, a high tension circuit and a sparking device connected therein; of an intermediate coil between the primary and the secondary windings of the alternating current generator and connecting therewith; an independent source of electrical current; a commutator, an electrical conduit connecting it with the terminal of the primary armature winding of the alternating current generator, electrical conduits from and to the independent source of electric current to and from the commutator; a switch therein and an electrical conduit from the cut out terminal of the switch to the alternating current generator, substantially as herein shown and described.

5. The combination in an electrical ignition system for internal combustion engines comprising an alternating current generator, a primary circuit, an interrupter in the primary circuit, a high tension circuit and a sparking device connected therein; of a coil having its terminals joined with the terminals of the primary and of the secondary armature windings of the alternating current generator, an independent source of electrical current, a conduit therefrom connecting it with the joined terminals of the coil and of the secondary armature winding of the generator; a switch in the conduit, and an electrical conduit completing the cir-

cuit of the independent source of electrical current, substantially as herein shown and described.

6. The combination in an electrical ignition system for internal combustion engines comprising an alternating current generator, a primary circuit, an interrupter in the primary circuit, a high tension circuit and a sparking device connected therein; of a coil 10 having its terminals joined with the terminals of the primary and of the secondary armature windings of the alternating current generator, a commutator electrically

connected with the joined terminals of the coil and of the secondary armature winding 15 of the generator; an independent source of electrical current; electrical conduits from and to the independent source of electric current to and from the commutator, and a switch in the conduit, substantially as herein 20 shown and described.

Correction in Letters Patent No. 1,178,067.

It is hereby certified that in Letters Patent No. 1,178,067, granted April 4, 1916, upon the application of Eugene Gassmann, of Brooklyn, New York, for an improvement in "Electrical Ignition Systems," an error appears in the printed specification requiring correction as follows: Page 3, lines 40-43, strike out the words "and in case of a break in the operation of a magneto, the device may be operated as a single (battery) ignition acting in both cases the same way" and insert the words *(magneto) ignition*; and that the said Letters Patent should be read with this correction therein that the same may conform to the record of the case in the Patent Office.

Signed and sealed this 9th day of May, A. D., 1916.

[SEAL.]
